UNITED STATES PATENT OFFICE.

WILLIAM DISNEY, OF CINCINNATI, OHIO.

SHADE-HANGER.

SPECIFICATION forming part of Letters Patent No. 730,241, dated June 9, 1903.

Application filed July 29, 1902. Serial No. 117,515. (No model.)

To all whom it may concern:

Be it known that I, WILLIAM DISNEY, a citizen of the United States, and a resident of Cincinnati, in the county of Hamilton and State 5 of Ohio, have invented a new and Improved Shade-Hanger, of which the following is a full, clear, and exact description.

My invention relates to shade-hangers for windows, my object being more particularly 10 to produce an adjustable shade-hanger and to prevent the free ends thereof from wearing upon the woodwork of the window.

Reference is to be had to the accompanying drawings, forming a part of this specification, 15 in which similar characters of reference indicate corresponding parts in all the figures.

Figure 1 is a front elevation of a window equipped with my invention and seen from the inside of the room. Fig. 2 is a side elevation of the same somewhat enlarged. Fig. 20 3 is a fragmentary plan view, partly in section, of the same; and Fig. 4 is a fragmentary section, somewhat enlarged, upon the line 4 4 of Fig. 1 looking in the direction of the 25 arrow.

The frame of the window is shown at 1 and is provided with a pulley 2 and cord 3 in the usual manner. Another cord 4 is secured within an eye 5, which is held in the rod 6, 30 forming the lower border of the shade 7. This shade is rolled upon the longitudinal roller, which is mounted upon the bearings 9 in the usual manner. These bearings are supported by the end brackets 10 11, which are in turn mounted upon the respective ends of the longitudinal rod 12. A suspension-bracket 13, provided with a semicircular bearing 14, is engaged by a screw 15 and nut 16, the screw 15 being free to move in the slot 21 for the 35 purpose of rendering the suspension-bracket 13 adjustable relatively thereto. A plate or bearing 17, preferably of rubber, is mounted upon the upper portion of the suspension-bracket 13, and through the plate and bracket 40 the cord 3 passes and is provided with a knot 19, as indicated more particularly in Fig. 2. The suspension-bracket is also provided with ears 20 for the purpose of holding the plate or bearing 17 in position.

Hollow cup-like members 22 are secured rigidly upon the brackets 10 11 for the purpose of supporting the same. The cavities

23 of these members engage directly the respective ends of the longitudinal rod 12. Screws 24, carried by these hollow members, 55 engage slots 25 at the respective ends of the longitudinal rod 12. The object of this arrangement is to make the end brackets 10 and 11 adjustable relatively to the rod 12. Bearing-brackets 26 27 are mounted upon the end 60 brackets 10 11 and are provided with concave disks 28 29, which loosely clamp the spherical body 30, the same acting as an antifriction-roller.

My device is used as follows: The cord 3 is 65 adjusted by hand to such a position that the suspension-bracket 13 is maintained at any desired level. As the suspension-bracket 13 supports the horizontal rod 12 and this rod by means of the brackets 10 and 11 supports the roller 8, having the shade rolled thereon, it is clear that the top of the shade may be placed upon any desired horizontal line. The cord 4 may then be adjusted in the usual manner, so as to pull the shade down or to 70 allow the same to coil upon the roller in the usual manner. By loosening the screws 24 the distance apart of the brackets 10 11 can be regulated at will, and the members 22 can be moved telescopically upon the ends of the 75 rod 12 and clamped thereon by means of the screws 24. The position of the suspension-bracket 13 may also be changed relatively to the general length of the roller and the rod 12, so as to balance the same exactly, thereby 80 preventing any tendency of either end of the roller to sag downward.

Suppose, now, that the operative notices that the shade and rod 12 are for some reason 85 out of alignment. The screws 24 25 are loosened and the adjustment made as above described. If the shade is not properly balanced upon the suspension-bracket 13, it is adjusted by means of the screw 15.

When the wind blows the shade or it is 90 moved accidentally by any cause or is purposely moved by means of the cords 3 and 4, the spherical members 30 are free to roll upon the woodwork 1, thereby reducing friction to a minimum and preventing the possibility of any movable part catching upon the woodwork should the same happen to be rough, thereby tending to destroy the alignment of 95 the shade.

It will be noted that the pressure exerted by the upper portion of the suspension-bracket is sustained by the cord 3, so that the position of the center of gravity of any or all parts is 5 immaterial. In other words, the shades heretofore used must exert pressure upon the ledge of the window or upon some other fixture, whereas in my shade no such support is needed, the pressure of the cord being all the 10 support needed.

Having thus described my invention, I claim as new and desire to secure by Letters Patent—

1. A shade-hanger comprising a shade-roller, a longitudinal rod provided with adjustable end brackets for supporting said roller, bearing-brackets projecting from one end of said end brackets and provided with rolling bodies, a suspension-bracket mounted 15 upon said longitudinal rod, and means controllable at will for shifting said suspension-bracket relatively to the general length of said longitudinal rod.

2. A shade-hanger comprising a shade-roller, a longitudinal rod, end brackets carried by the rod for supporting said roller, means for adjustably securing the said end brackets to said longitudinal rod, a suspension-bracket loosely mounted upon said longitudinal rod, and means controllable at will 20 for adjusting said suspension-bracket relatively to said longitudinal rod.

3. A shade-hanger comprising a shade-roller, a longitudinal rod, end brackets carried by the rod for supporting said roller, means for adjustably securing the said end brackets to said longitudinal rod, bearing-brackets projecting from one end of said end brackets, rolling bodies mounted within said 25

brackets, a suspension-bracket mounted upon 40 said longitudinal rod, and means controllable at will for adjusting said suspension-bracket relatively to said longitudinal rod.

4. A shade-hanger, comprising a rod, roller-carrying brackets adjustably secured to the 45 ends of the rod, and a suspension-bracket having a semicircular bearing engaging the rod and adjustably secured thereto, as set forth.

5. A shade-hanger, comprising a rod, roller-carrying brackets provided with inwardly-projecting sockets into which the ends of the 50 rod project, and means for adjustably securing the ends of the rod in the sockets, and a suspension-bracket adjustably secured to said rod, as set forth.

6. A shade-hanger, comprising a rod, roller-carrying brackets provided with sockets in 55 which the ends of the rod are adjustably secured, a suspension-bracket adjustably secured to the said rod, bearing-brackets projecting from the brackets on the ends of the rod, and rolling bodies mounted in the said brackets, as set forth.

7. A shade-hanger, comprising a rod, roller-carrying brackets adjustably secured to the 60 ends of the rod, a suspension-bracket adjustably secured to the rod, bearing-brackets secured to one end of each roller-carrying bracket and provided with concave disks, and spherical bodies mounted between the disks 70 of the said brackets, as set forth.

In testimony whereof I have signed my name to this specification in the presence of two subscribing witnesses.

WILLIAM DISNEY.
